UNITED STATES PATENT OFFICE.

HERAULT A. TRESTER, OF MILWAUKEE, WISCONSIN, ASSIGNOR TO METAL FORMS CORPORATION, OF MILWAUKEE, WISCONSIN, A CORPORATION.

ROAD RAIL.

Application filed March 15, 1922. Serial No. 544,025.

To all whom it may concern:

Be it known that I, HERAULT A. TRESTER, a citizen of the United States, residing at Milwaukee, in the county of Milwaukee and State of Wisconsin, have invented certain new and useful Improvements in Road Rails, of which the following is a specification.

The present invention relates to certain new and useful improvements in the construction of what are commonly known in the art of road building as road rails or forms. In the construction of roads from plastic material such as concrete, these rails are ordinarily positioned upon the sub-grade at opposite sides of the road and the concrete or plastic material deposited and distributed between the rails. After the concrete has set the rails are removed so that they are used progressively as the building of the road proceeds. It has been found advantageous to mount quite a number of the road building appliances, such as sub-grade planers and finishing machines upon wheels or trucks which travel upon the rails, so that the rail members not only serve as forms for the edge portions of the concrete road or pavement, but are called upon to support and carry rather heavy loads.

Keeping the foregoing considerations in mind, the object of the invention has been to provide a road rail which embodies novel features of construction whereby a maximum degree of strength and stability is obtained for the amount of material which is used. The road rail will carry and support heavy loads without being bent or distorted out of shape and can be used repeatedly so that it constitutes what is practically a permanent equipment for the contractor using the same.

With the above and other objects in view the invention consists of certain combinations and arrangements of the parts as will more fully appear as the description proceeds, the novel features thereof being pointed out in the appended claims.

For a full understanding of the inven-

tion reference is to be had to the following description and accompanying drawings 50 in which:

Figure 1 is a perspective view of a road rail which is constructed in accordance with the invention.

Figure 2 is a detail view of one end of 55 the rail.

Figure 3 is an enlarged transverse sectional view through the rail, taken at a point intermediate of a pair of the box or brace members.

Figure 4 is a similar view which is taken on a line extending through one of the boxes or brace members.

Corresponding and like parts are referred to in the following description and indicated on all of the views by like reference characters.

The improved road rail is adapted to be formed of sheet material which may be of any suitable thickness or gauge, depending upon the loads to be carried by the rail and the conditions under which it is to be used. The numeral 1 designates the rail base and the working face 2 of the rail extends upwardly from the inner edge of the base. The rail head 3 is formed by bending the sheet metal rearwardly at the top of the working face, and a depending flange 4 extends diagonally downward from the outer edge of the head. The base 1, working face 2, head 3 and depending flange 4 may all be readily formed by suitably bending a single blank of sheet material as is indicated by the drawing.

The rail is provided at intervals throughout its length with the hollow box members 5 which perform the double function of stiffening and reenforcing the rail and also of receiving the stakes. These box members 5 extend transversely of the rail and have an arched or inverted U shaped formation which gives them great inherent strength. It will also be observed that they have a tapered formation and that the arched top portions thereof are inclined 95 downwardly and rearwardly away from the

working face 2. The lower edges of the box members 5 are formed with outstanding flanges 6 which are riveted to the base 1, and the inner ends of the box members 5 abut against the upright wall of the rail and are provided at the sides thereof with flanges 7 which are riveted or otherwise securely fastened to the wall 2. The flared inner ends of the box members 5 have a height which corresponds substantially with the height of the rail so that the upright walls 2 of the rails are braced by these boxes throughout their entire height.

The depending flange 4 of the head 3 terminates in an outwardly inclined lip 8 which rests upon the inclined upper portions of the box members 5 and is rigidly connected thereto in some suitable manner as by means of the rivets 9. This flange thus has a firm support at its lower edge and the flange acts in an obvious manner to stiffen and reinforce the head 3 of the rail. A maximum strength is obtained for the material used and the head of the rail is such that it will support heavy superimposed loads and withstand much battering and hard usage without becoming bent or distorted out of shape.

The base 1 may extend over a comparatively large area so as to obtain a firm bearing upon the subgrade and corresponding stake receiving openings 10 are formed in the rear ends of the box members 5 and the base 1. These openings are adapted to receive the usual stakes 11 upon which the rails are supported and any suitable means may be provided for locking the rails in position upon the stakes. In the present instance the sides of the hollow box members 40 are provided with corresponding slots 12 which are adapted to receive wedge members 13. The wedge members can be readily driven into and out of position and are adapted to grip the sides of the stakes to support the rails in proper position. The hollow box members are spaced apart at suitable intervals to stiffen and reinforce the rail in the desired manner and the parts are rigidly fastened together so that a construction which has a great deal of inherent rigidity is obtained.

These rails are formed in suitable lengths which are adapted to be used interchangeably and which are held together and maintained in alignment by means of suitable couplings. As indicated by Figure 1 of the drawing, one end of each of the rail sections is provided with a projection 14 which is adapted to telescope within the end of an adjacent rail section for the purpose of holding the two rail sections accurately in alignment. The projection or joint member 14 may be conveniently formed from an arched strip of sheet material which is bent to conform with the shape of the rail and has the

arched top thereof arranged under the rail head 3. One side or arm of this member is riveted or otherwise secured to the upright wall 2 of the rail, while the other side of the member forms a strap which connects the depending flange 4 to the base 1. This strap braces the parts at the joint connection between the meeting ends of adjacent rail sections, and is provided at its lower end with an outstanding tongue 14^a which is riveted to the base. The opposite end of each of the rail sections, as is illustrated by Figure 2, is adapted to receive the joint member or projection 14 of an adjacent rail section, and is provided upon its base with an upstanding lug 15 which is slightly spaced from the upright wall 2 and is adapted to engage and interlock the corresponding lower end of the projection 14. The arched upper end of the coupling member 14 interlocks with the head portion of the rail and one of the lower ends of the coupling member interlocks with the lug 15, so that the abutting ends of adjacent rail sections are maintained in an accurate alignment with each other. These rail sections may be used interchangeably with other rail sections having corresponding coupling ends, and the other rail sections may be of either a heavier construction or a lighter construction, as may be desired. This manner of constructing the rails enables great rigidity and strength to be obtained in a comparatively light weight rail, although it will be obvious that where greater strength is required thicker and heavier material can be used. The rail head is stiffened and formed in such a manner that it is capable of resisting the battering action of wheels and trucks thereon, and the rail is well adapted for the support of such road building appliances as subgrade planers and surface finishing machines which are commonly mounted to travel upon these rails.

It will be noted that owing to the inclination of the hollow brace boxes 5 the head of the rail is in effect stiffened and re-inforced at intervals by diagonal braces. It will be obvious from an inspection of Figures 3 and 4 of the drawing that the upper ends of the hollow boxes 5 extend diagonally between the inner edge of the head 3 of the rail and the lower edge of the flange 4 at the outer portion of the rail. The diagonal arrangement and disposition of these braces results in imparting rigidity to the head which enables it to carry heavy loads and withstand hard usage.

While one possible embodiment of the invention has been illustrated and described in detail it will be obvious that many modifications and changes can be made in the details of construction without departing in any manner from the spirit of the invention.

Having thus described my invention what

I claim as new and desire to secure by Letters Patent is:

1. A rail form of the character described, including a body portion formed with an upright working face, and a series of transversely disposed hollow arch shaped reinforcements engaging the back of the working face and inclined downwardly and rearwardly therefrom, the front end of the arched reinforcements extending the full height of the upright working face and the inclined tops thereof forming substantially diagonal brace members. 70
2. A rail form of the character described, including a body member formed with an upright working face, a series of transverse reinforcements extending rearwardly from the working face, and a rail head provided at the top of the working face and formed with a depending flange which is spaced from the base throughout its length and which rests upon and is secured at intervals to the reinforcements. 80
3. A rail form of the character described, including a body portion formed with an upright working face and a rearwardly extending head at the top of the working face, said head having a depending flange at the free edge thereof which is spaced throughout its length from the body portion, and a series of transversely disposed hollow arch shape reinforcements extending rearwardly from the back of the working face and inclined downwardly, the forward ends of the arched reinforcements extending the full height of the working face, the depending flange of the head engaging the top of said reinforcements. 90
4. A rail form of the character described, including a body member formed of sheet metal and comprising a base, working face and head, the head being provided with a depending flange which is spaced throughout its length from the base, and a series of hollow and transversely disposed reinforcements applied at intervals to the base and back of the working face, said reinforcements extending the full height of the working face and being inclined downwardly and rearwardly from the working face, and projecting beyond the head, the projecting portions of the reinforcements being provided with stake engaging means and the depending flange of the head being secured to the top of the reinforcements. 100
5. A rail form of the character described, including a body member formed of sheet metal and comprising a base, working face and head, the head being formed with a depending flange having an angularly disposed lip at the free edge thereof and which is spaced throughout its length from the base, a series of transversely disposed arched reinforcements applied at intervals to the base and back of the working face and tapered 110
- toward the back of the rail, the large ends of the reinforcements extending substantially the full height of the working face and the lip of the depending flange of the head being secured to the top of the reinforcements. 120
6. A rail form of the class described, comprising a body provided with an upright working face and a rearwardly extending head projecting from the upper edge of said face, together with a base extending laterally from the lower edge of the said face, and stake boxes located at intervals along the body member and of substantially inverted U-form, said stake boxes being secured to the base and having their top portions inclining upwardly and in engagement with the outer side of the upright working face of the body member. 130
7. A rail form of the character described, including a section formed with a base, working face and head, a coupling tongue projecting from one end of the section and having an arched formation, one side of the coupling tongue being secured to the back of the working face while the other side thereof extends between the head and the base and reinforces the head, the opposite end of the section being adapted to receive the coupling tongue of an adjacent section, and a lug on the base of the opposite end of the section adapted to engage and position the coupling tongue. 140
8. A rail form comprising a body member having a base, an upright working face extending from said base and outwardly projecting rail head leading from the upper portion of the said working face, and a stake box applied to the said form body and comprising a substantially inverted U-shaped member the sides of which are formed with horizontal lateral flanges secured to the base aforesaid, and said sides also having vertical lateral flanges which are secured to the outer side of the working face of the body member of the form, said stake box being provided with a stake socket therein. 150
9. A rail form comprising a body member consisting of a base from which upwardly projects an upright working face at the top of which is located a lateral rail head, and stake boxes located at intervals along the body member and consisting of structures of substantially inverted U-form, with means for attaching said structures to the base and to the working face of the rail form at the outer side of said face, the top of each box inclining upwardly and inwardly toward the rail head to a point where it meets the outer side of the working face adjacent to where said rail head extends from said face, whereby each box forms a rigid bracing means for the form intermediate its head and base. 160
10. In a rail form, a body member con-

- sisting of a relatively wide base having an upwardly projecting working face extending from one edge thereof and formed with a lateral head flange much narrower than the said base, and a series of attached bracing devices consisting of members rigidly secured to the base and inclining upwardly

therefrom to a point beneath the said head flange, and rigidly attached to the outer side of the working face substantially as described. 10

In testimony whereof I affix my signature.

HERAULT A. TRESTER.
